UNITED STATES PATENT OFFICE.

WM. HENRY HALL, OF NEW YORK, N. Y.

IMPROVED BOTTLE-STOPPER.

Specification forming part of Letters Patent No. 44,184, dated September 13, 1864.

To all whom it may concern:

Be it known that I, WM. H. HALL, of the city, county, and State of New York, have invented a new and Improved Bottle-Stopper; and I do hereby declare that the following is a full, clear, and exact description thereof, which will enable those skilled in the art to make and use the same, reference being had to the accompanying drawings, forming part of this specification, in which—

Figure 1 represents a vertical central section of my invention when applied to a bottle or vial: Fig. 2 is a detached perspective view of the flanged discharge-tube, which constitutes the subject-matter of my invention.

Similar letters of reference indicate corresponding parts.

This invention consists in the use of a flanged discharge-tube which is secured in an ordinary stopple by screwing, or in any other suitable manner, and which is provided with a screw-cap, in such a manner that by removing the screw-cap, the contents of the bottle or vial can be poured out in small or large quantities without removing the stopple, and the liquid is prevented from adhering to the upper edge of the discharge-tube and running over the sides of the bottle or vial, which it is liable to do in pouring liquid from the neck of the bottle or vial, and by replacing the cap the bottle or vial is firmly and hermetically closed.

A represents a bottle or vial which is stopped or closed by an ordinary cork or other stopple, B. This stopple is perforated through its longitudinal center with a hole, a, to receive the lower shank of my flanged discharge-tube C. This discharge-tube is cast of tin or other suitable material, and it is screwed on both ends above and below the flange, as clearly shown in Fig. 2 of the drawings. The lower shank or end of the tube screws into the stopple, and it is screwed down until the flange fits closely to the upper end of said stopple, as clearly shown

in Fig. 1 of the drawings. The upper shank or end of my discharge-tube is provided with a screw-cap, D, which screws over it, as seen in Fig. 1, and this cap is furnished with a packing-piece, b, of leather, india-rubber, or other suitable material, which, when the cap is screwed down, presses tight upon the edge of the discharge-tube and closes the same hermetically. The stopple is inserted into the neck of the bottle or vial to be closed until the flange of my discharge-tube strikes the upper edge of said neck, and it is not removed until the bottle or vial is to be recharged. In order to pour out some of the contents of the bottle or vial, the stopple is not removed, nothing being required but to take off the screw-cap D. The liquid can now be poured out with perfect accuracy. There is no danger of spilling, and the exterior of the bottle is easily kept clean, since the liquid is not liable to adhere to the edge of the discharge-tube and to run down over the outside of the bottle or vial, which it does when it is poured directly from the neck.

By the use of my discharge-tube the stopples are saved, since they have not to be removed whenever it is desired to pour out some of the contents of the bottle or vial. The bottles or vials are hermetically sealed, and their contents are not liable to lose their strength, and the expense of my discharge-tube is trifling compared with its advantages.

I claim as new and desire to secure by Letters Patent—

The use of the flanged discharge-tube C with screw-cap D, in combination with an ordinary stopple, B, applied and operating substantially as and for the purpose set forth.

WM. HENRY HALL.
